CLAIM

I claim the ornamental design for a car alarm controller holder, as shown.

DESCRIPTION

FIG. 1 is a perspective view of a car alarm controller holder showing my new design;

FIG. 2 is a front elevational view thereof;

FIG. 3 is a rear elevational view thereof;

FIG. 4 is a right side elevational view, with the left side elevational view being a mirror image thereof;

FIG. 5 is a top plan view thereof; and,

FIG. 6 is a bottom plan view thereof.

1 Claim, 1 Drawing Sheet

FIG. 1.

FIG. 2.

FIG. 3.

FIG. 4.

FIG. 5.

FIG. 6.
